2,179,652

TELEPHONE SYSTEM

William H. Waite, Lynbrook, N. Y., assignor to
 Dictograph Products Company, Inc., New York,
 N. Y., a corporation of Delaware

Application January 7, 1938, Serial No. 183,744

10 Claims. (Cl. 179—39)

This invention relates to telephone systems and has particular reference to intercommunicating telephone systems in which a master station may communicate with any one of a number of substations and any substation may communicate with the master station.

As the number of substations is increased the wiring increases proportionately, thus greatly increasing cost, materials, and installation and servicing problems and placing a practical limit on the number of substations. Any means for decreasing the amount of necessary wiring without impairing the operation facility of the system accordingly not only would decrease cost and materials and simplify installation and servicing, but would also render the system much more flexible and enable the use of a greater number of substations when required.

A system of this general nature, in which a considerable saving of wire is effected with many of the attendant advantages enumerated, is disclosed in Patent No. 2,007,990, issued July 16, 1935, to William H. Waite. That system is described as particularly applicable to a hospital telephone system, although not limited to that use, and requires only one conductor between the master station and each of the substations with a switching control relay, in addition to the necessary common conductors, thus effecting a wire saving of approximately 45%. However, in hospital systems a call is initiated by the patient and is completed by the master station for obvious reasons, no provision being made for initiation of the call from the master station, except by signal responded to by the patient, who then actually initiates the call, so that while there may be direct intercommunication between the master station and substation, the facility provided by two-way initiation of calls is lacking in such system.

In accordance with the present invention an intercommunicating telephone system is provided for two-way initiation of calls between a master station and any one of a plurality of substations, which embodies the advantages of minimum wiring and attendant saving of first and installation cost and labor of the system of the aforementioned patent, and also has all of the operating advantages afforded by two-way initiation of calls.

In a preferred embodiment of the invention, each substation is connected to the master station by only one single conductor which is individual to that substation and is additional to the common conductors between all substations and

the master station. Two relays, each individual to the corresponding master and substation are interposed in each said single conductor and are energized upon operation of either a substation or corresponding master station calling switch to temporarily break the normal talking circuit, which is immediately restored and completed when the answering station responds, this arrangement enabling the simplification effected by the reduced wiring. Secrecy provisions are made and other improvements are included which augment the efficiency and operating facility of the system.

For a more complete understanding of the invention, reference may be had to the accompanying drawings in which:

Figure 1 is a schematic electrical diagram of one form of the telephone system of this invention;

Fig. 2 is a simplified schematic diagram of the telephonic circuit;

Fig. 3 is a fragmentary schematic electrical diagram of an optional form of substation circuit; and

Fig. 4 is a fragmentary schematic diagram of an adaptation of the master station circuit.

Referring to Figure 1, the master station is designated M and the substations, of which there may be any desirable number, such as the four shown, are designated A, B, C and D. The master station M is provided with corresponding substation keys or switches a, b, c and d, with their corresponding visual signal flags or other indicators a₁, b₁, c₁ and d₁. Inasmuch as the substations are identical, the description of one of them, A, will suffice.

Substation A includes a transmitter or microphone 10, a receiver 11, either separate or handset type, and a key-operated switch 12, either directly manually operable or operable by movement of the receiver or handset. Substation switch 12 consists of two sides or parts, one of which has five contact springs and the other four. The former comprises a spring 13 normally disengaged from spring 14, which normally engages spring 15. A fourth spring 16 is normally disengaged from a fifth spring 17. Springs 14 and 17 are connected by an insulating bar 18 so that when switch 12 is operated, the springs 14 and 17 simultaneously engage springs 13 and 16, respectively, and spring 14 disengages spring 15. The other side of the substation switch 12 includes contact springs 20 and 22 which are normally disengaged from contact springs 19 and 21, respectively, connected by insulating bar 23 for simul-

taneous operation when the key is manipulated to engage switch contacts 20 and 22, respectively.

First contact spring 13 of substation key switch 12 is connected by wire 46 to the common positive line 45, while second contact spring 14 is connected by wire 24 to local relay 25, the other side of which is connected by wire 49 through relay 50 of corresponding signal flag a_1 at the master station M, and wire 51 to switch contact 52 of the corresponding master station key a . This contact 52 normally engages contact 53 which is connected by wire 55 to common negative line 44.

The third contact spring 15 of the substation switch 12 is connected by wire 43 to the common negative line 44, while fourth contact spring 16 is connected by wire 40 to relay 25 contact spring 33, which normally engages contact spring 34, connected by wire 41 to a talking line 42 which is common to both the substations and the master station.

The fifth spring 17 is connected by wire 39 through the local transmitter or microphone 10 to contact spring 22 on the other side of the substation key. The talking circuit of transmitter 10 also traverses the substation receiver 11 through wire 35 connected to contact spring 18. Contact spring 21 is connected by wire 89 to the common negative line 44. Contact spring 20 is connected by wire 36 to relay contact spring 28 engaging contact spring 32, connected by wire 37 to common talking line 38.

Relay 25 contact spring 30 is insulated by block 29 from contact spring 28, and is normally disengaged from cooperating contact spring 31 connected through buzzer 48 by wire 47 to one side of relay 25 coil. Contact spring 30 is connected through resistor 88 and wire 90 to common positive line 45. The armature 26 of relay 25 is connected by insulating bar 27 to contact spring 28 so that armature 26 and spring 28 operate as a unit.

The individual substations A, B, C and D are each provided with the single direct wire 49' which, like wire 49 of station A, is connected to a relay at the master station corresponding to the substation. The wires 43', 46', 41', 37', 89', and 90', on substations B, C, and D correspond to the wires 43, 46, 41, 37, 89, and 90 of substation A.

The master station key switch a contact spring 52 is adapted to engage contact spring 54 connected through wire 83, relay 72 and wire 69 to common positive line 45. Key switch a contact spring 51 is adapted to engage spring 56, which completes a circuit from common negative line 44, normally engaged springs 61 and 59, wire 58, spring 56, spring 57, wire 70, relay 71 and wire 69 to common positive line 45.

When flag relay 50 is energized, its armature 87, connected by insulating block 60 to spring 61, disengages spring 61 from spring 59 and engages it with spring 62. This completes a circuit from common negative line 44, through springs 61 and 62, wire 63, normally closed switch 64, wire 65, normally closed spring contacts 66 and 67, local buzzer 68 and wire 69 to common positive line 45, between which and common positive line 44 is connected the signal battery 83. The buzzer 68, thus energized, signals the master station that it is being signalled and raised flag a_1 indicates the calling substation.

When the relay 71 is energized, its armature 76 engages a contact spring 75, connecting common talking line 42 through the armature 76, contact spring 75, wire 77, impedance or choke coil 78, and wire 79 to the positive terminal

of the talking battery 80, the negative terminal of which is connected to common negative wire 44. The master station receiver 86, which is preferably a loud speaker, is connected in series with a condenser 85, and both are connected in parallel with impedance coil 78.

Energization of relay 71 also causes its armature 76 to engage contact spring 73 with contact spring 74 to complete a circuit from common talking line 38 through engaged contact springs 73 and 74, wire 81, local transmitter or microphone 82, and wire 79 to talking battery 80.

In operation of the arrangement of Fig. 1, and assuming that A desires to communicate with the master station M, the substation key 12 is manipulated, completing a circuit traceable from common positive line 45, wire 46, contact 13, contact spring 14, wire 24, local relay 25, wire 49, substation flag a_1 relay 50, wire 51, switch key a closed contacts 52 and 53, wire 55 and common negative line 44, thus energizing the respective substation and master station relays 25 and 50. Armature 87 of called master station relay 50 raises flag a_1 indicating the calling substation A and causes the spring 61 to disengage contact 59 and engage contact 62, thus completing a circuit from the common negative line 44, spring 61, contact 62, wire 63, closed switch 64, wire 65, contact 66, armature 76 of the relay 72, buzzer 68 and wire 69 to common positive line 45, thus energizing the master station buzzer 68, which may be silenced by opening switch 64.

Energizing of calling substation A relay 25 breaks the normal talking circuit between the microphone or transmitter 10 and common talking line 42, by disengaging contacts 33 and 34. Similarly, the normal listening circuit between the substation receiver 11 and common talking line 38 is broken by the disengagement of contacts 28 and 32 by relay 25. When the master station responds by manipulating the key a corresponding to raised flag a_1 , the talking and listening circuits are reestablished by the de-energized relays 25 and 50, due to reengagement of relay 25 contacts 33 and 34 and 28 and 32. Key a also disengages contacts 52 and 53, resetting flag relay 50 and breaking the buzzer 68 circuit through contacts 61 and 62.

Simultaneously spring 61 engages contact 59, completing a circuit traceable from common negative line 44 through spring 61, contact 59, wire 58, contact 56, spring 57, wire 70, relay 71, wire 69 and common positive line 45. Relay 71 armature 76 engages contact 75 and also causes engagement of spring 73 and contact 74, so that the master station receiver 86 is connected to common talking line 42, and master station transmitter 82 is connected to common talking line 38. The master station talking or sub-station listening circuit is now completed from common negative line 44 through the talking battery 80, wire 79, master station microphone or transmitter 82, wire 81, contacts 73 and 74, common talking line 38, wire 37, spring contacts 32 and 28, wire 36, spring contacts 20 and 19, wire 35, sub-station receiver 11, contacts 22 and 21, and wire 89 back to common negative line 44.

The sub-station talking or master station listening circuit is traceable from common negative line 44, talking battery 80, wire 79, parallel impedance coil 78 and receiver 86 and condenser 85, wire 77, contacts 75 and 76, common talking line 42, wire 41, contacts 34 and 33, wire 40, contacts 16 and 17, wire 39, sub-station microphone 75

or transmitter 10, contacts 22 and 21 and wire 88 back to common negative line 44.

The restoration of the keys or switches at the master station and sub-station restores the circuits to their normal inoperative condition.

Assuming that master station M wishes to call a sub-station such as A, manipulation of key a engages spring 52 with contact 54, completing a signalling circuit traceable from common positive line 45, wire 69, relay 72, wire 83, contacts 54 and 52, wire 51, flag a₁ relay 50, wire 49, sub-station relay 25, wire 24, contacts 14 and 15 and wire 43 to common negative line 44. The relays 25 and 50 are energized as before, breaking both normal talking circuits. The armature 26 of the relay 25 actuates spring 28 to engage contact 30 with 31 through the insulating piece 29. This closes a signalling circuit from common positive line 45, wire 90, resistor 88, contacts 30 and 31, the sub-station buzzer 48, wires 47 and 24, contacts 14 and 15 and wire 43 to common negative line 44, thus energizing the buzzer 48. Manipulation of sub-station key 12 breaks the contact between 14 and 15, and engages contacts 13 and 14, thus simultaneously deenergizing the sub-station buzzer 48, and the two relays 25 and 50. This reestablishes the two talking circuits as described between the two stations.

It will be observed that the normal talking and listening circuits of the sub-station are first broken by relay 25 and then restored by deenergization thereof when the talking and listening circuits are completed, thus effecting the saving in wire heretofore described. Another important feature is that conversation between any sub-station and the master station is entirely secret. If a second sub-station switch is operated while the master station and a sub-station circuits are completed it will act to operate the relays 25 and 50 in the single line 49 to the master station, thus energizing the master station buzzer 68 and also disconnecting that station from the talking lines 38 and 42. The talking circuit remains disconnected due to this interruption until the operator at the master station operates the key corresponding to the second sub-station to reclose the circuit and communication may proceed.

Fig. 2 illustrates the simplified talking circuit, in which the substation receiver 11 and the master station transmitter 82 are in series, while the substation transmitter 10 and the master station receiver 86 are also in series, the talking battery 80 being common to both circuits. The impedance coil 78 permits the flow of direct current, but has a high impedance to the voice currents, while the condenser 85 prevents the flow of direct current through the loud speaker 86 and at the same time offers very low impedance to the voice currents. Thus, direct current is kept out of the loud speaker 86, and most of the voice current is shunted through it.

Fig. 3 illustrates the use of the receiver hook as the key to actuate the switch 12 at the sub-station. The circuit is the same as in Fig. 1 with the exception that the spring 17 is replaced by the receiver hook 104. The receiver 11 with the microphone or transmitter 10 may also be combined in a hand set, in which case hook 104 may be a handset cradle. The removal of the receiver or handset from the hook 104, energizes the relays 25 and 50 in the same manner as when the key 12 is manually manipulated. Similarly, re- placement of the receiver or handset on the hook

104 restores all the circuits to their normal inoperative position.

Fig. 4 illustrates an alternative arrangement at the master station for disconnecting the loud speaker 86 and the microphone or transmitter 82 and substituting a hand set for private conversation. For loud speaker operation the talking circuit includes the usual wire 77 from talking line 42, spring 95 normally engaging contact 96, a wire 99, the microphone or transmitter 82, the talking battery 80 and the negative line 44. The listening circuit is traced from common talking wire 38, wire 81, through a spring 92 normally engaging contact 91, wire 100, an impedance coil 78, in parallel with condenser 85 and the loud speaker 86, and talking battery 80 to common negative line 44. For private conversation the handset is removed from the hook 101, thus breaking the loud speaker circuit and establishing the new handset circuit. In this case, the transmitter circuit is traced from wire 77, spring 95, contact 94, wire 102, the private transmitter or microphone 98 and talking battery 80 to the negative line 44. The receiver circuit is traced from wire 81, through spring 92 engaging the contact 93, wire 103, the private receiver 97 and talking battery 80 to the negative line 44.

It will be seen that the new telephone system requires a minimum of wiring, while at the same time it insures complete privacy in communication between any substation and the master station. Not only is it possible for a sub-station to signal and converse with the master station, but it is possible for the master station to signal and converse with any one of the sub-stations without being overheard through another sub-station receiver.

While a specific embodiment has been presented in this application it is to be understood that the invention is not to be limited in any way thereby except as defined in the claims.

I claim:

1. In a telephone system, the combination of a master station, a plurality of substations, a plurality of conductors each connected to each substation and to the master station, a single conductor between each substation and the master station individual only to those substations, two relays in each said single conductor individual to the master station and the corresponding substation, a telephone instrument at the master station controlled by the corresponding relay, a telephone instrument at each substation controlled by the corresponding relay, and a switch in each said single conductor for operating the corresponding relays.

2. In a telephone system, the combination of a master station having a telephone instrument, a plurality of substations each having a telephone instrument, a plurality of conductors each connected to each substation and to the master station, a single conductor between each substation instrument and the master station instrument which is individual only to those instruments, two relays in each said single conductor, one of said relays being individual to the master station instrument for controlling the same and the other relay being individual to the corresponding substation for controlling the corresponding instrument, and a switch at the master station for operating the corresponding relays.

3. In a telephone system, the combination of a master station having a telephone instrument, a plurality of substations each having a telephone instrument, a plurality of conductors each con-

- 5 nected to each substation and to the master station, a single conductor between each substation instrument and the master station instrument which is individual only to those instruments, two 10 relays in each said single conductor, one of said relays being individual to the master station instrument for controlling the same and the other relay being individual to corresponding substation for controlling the corresponding instrument, and a switch at each substation for operating the corresponding relays.
4. In a telephone system, the combination of a master station having a telephone instrument, a plurality of substations each having a telephone 15 instrument, a plurality of conductors each connected to each substation and to the master station, a single conductor between each substation instrument and the master station instrument which is individual only to those instruments, two 20 relays in each said single conductor, one of said relays being individual to the master station instrument for controlling the same and the other relay being individual to corresponding substation for controlling the corresponding instrument, and switches at the substations and the master station for the operation of the corresponding relays.
5. In a telephone system, the combination of a master station having a telephone instrument, a plurality of substations each having a telephone 25 instrument, a plurality of conductors each connected to each substation and to the master station, a single conductor between each substation instrument and the master station instrument which is individual only to those instruments, two relays in each said single conductor, one of 30 said relays being individual to the master station instrument for controlling the same and the other relay being individual to corresponding substation for controlling the corresponding instrument, and switches at the substations and the master station for the operation of the corresponding relays.
6. In a telephone system, the combination of a master station having a telephone instrument, a plurality of substations each having a telephone 35 instrument, a plurality of conductors each connected to each substation and to the master station, a single conductor between each substation instrument and the master station instrument which is individual only to those instruments, two relays in the said single conductor of each substation, operative connections between one of said relays and the master station instrument for controlling the latter, a second telephone instrument at each substation controlled by the corresponding second relay, and a switch for operating the relays.
7. In a telephone system, the combination of a master station having a telephone instrument, a plurality of substations each having a telephone 40 instrument, a plurality of conductors each connected to each substation and to the master station, a single conductor between each substation instrument and the master station instrument which is individual only to those instruments, two relays in the said single conductor of each substation, operative connections between one of said relays and the master station instrument for controlling the latter, a second telephone instrument at each substation controlled by the corresponding second relay, and a switch at the master station for operating the relays.
8. In a telephone system, the combination of a master station having telephone instruments, a plurality of substations each having telephone instruments, a normally closed circuit for each 45 substation instrument, a relay controlling said circuit, a switch for actuating said relay to break the normal circuit of at least one of the substation instruments, and a switch for restoring said relays to restore the normal circuit of said one substation instrument and establish a communication circuit between the said substation and master station instruments.
9. In a telephone system, the combination of a master station having telephone instruments, a plurality of substations each having telephone 50 instruments, a normally closed circuit for each substation instrument, a relay controlling said circuit, a switch at the master station for actuating said relay to break the normal circuit of at least one of the corresponding substation instruments, and a switch at the substation for restoring said relay to restore the normal circuit of said one substation instrument and establish a communication circuit between the said substation and master station instruments.
10. In a telephone system, the combination of a master station having telephone instruments, a plurality of substations each having telephone 55 instruments, a normally closed circuit for each substation instrument, relays at the substations and master station for controlling the circuits of the corresponding instruments, switches at the substation and the master station for actuating the corresponding relay to break the normal circuit of at least one of the corresponding substation instruments, and switches at the substation and the master station for restoring the corresponding relay to restore the normal circuit of said one substation instrument and establish a communication circuit between the said master station and substation instrument.

WILLIAM H. WAITE.

CERTIFICATE OF CORRECTION.

Patent No. 2,179,652.

November 14, 1939.

WILLIAM H. WAITE.

It is hereby certified that error appears in the printed specification of the above numbered patent requiring correction as follows: Page 4, first column, line 54, claim 6, for the word "such" read each; and that the said Letters Patent should be read with this correction therein that the same may conform to the record of the case in the Patent Office.

Signed and sealed this 12th day of December, A. D. 1939.
